GEORGE F. ROSE, OF HYNDSVILLE, NEW YORK.

TYPEWRITING MACHINE.

Application filed December 6, 1921. Serial No. 520,419.

This invention relates to typewriting machines and more particularly to the variety employing a carriage having a letter-spacing, feeding movement; one object of the invention being to provide an improved machine of this character with efficient means for locking the carriage and its associated parts against inadvertent strain or movement and possible injury through impacts or violent movements occasioned for example during the transportation of the machine.

Another object is to provide a machine of this type with means for not only locking the carriage against movement but also for disconnecting the mechanism controlling the feeding movement of the carriage from the latter and thus more effectively protecting the mechanism against injury during bodily movement of the machine.

A further object is the provision in conjunction with a portable type of machine of the above description and with the casing for transporting the same, of means operated automatically by the closing of the casing, for locking the carriage in position and disconnecting the feeding mechanism therefrom for the purposes set forth.

Still a further object is the provision of improvements of the character specified comprising but few parts of simple and effective construction and mode of operation, which can be readily applied, and of a comparatively low cost. The invention further consists in a novel arrangement of the various parts of the machine whereby an exceedingly small and flat machine of the non-folding type is provided having pivoted type bars arranged to strike on the upper front quarter of the platen, and also contemplates the provision of a simple, compact and efficient construction and arrangement of the carriage escapement and the universal bar mechanism for actuating the same. To these and other ends the invention resides in certain improvements and combinations of parts all as will hereinafter be more fully described, the novel features being pointed out in the claims at the end of the specification.

In the drawings:

Figure 1 is a rear elevation, partly broken away, of a typewriting machine embodying the present invention;

Figure 2 is a sectional elevation from

front to rear of the same, substantially on the line 2^a—2^a of Figure 1; and

Figure 3 is a view similar to Figure 2 showing the parts however in different positions.

Certain novel features of the machine illustrated form the subject matter of my co-pending applications, Serial No. 523,317, filed December 19, 1921 and Serial No. 521,227, filed December 9, 1921.

Similar reference numerals throughout the several views indicate the same parts.

The embodiment of the invention selected for the purposes of the present disclosure to illustrate the principles involved and a preferred practical application of the same, comprises a main frame indicated generally at 10, of the usual or any suitable construction, carrying a support or bridge 11, Figure 2, for the key levers shown at 12. The latter have pivotally connected with their rear ends links 13 the other ends of which are pivotally connected with type bars 14. The main frame carries also a transverse supporting wall or plate 15 on which is fixed a bracket 16 supporting the rear ends of the type bars for pivotal movement about an axis 17. The novel hanger bracket 16 for supporting the usual arcuate pivot wire or bail 17 is formed and secured to member or plate 15 as shown and claimed in my co-pending application Serial No. 523,317, and the novel key lever bridge is formed and mounted in the frame as shown and claimed in my application Serial No. 521,227 above referred to. The plate 15 is inclined upwardly and rearwardly so that the pivot wire or bail 17 will lie in a correspondingly inclined plane with the lowest point thereof at approximately the mean level of the key levers 12, thus permitting the bars to extend upwardly and forwardly when at rest without increasing the height of the machine and affording space below the level of the bars for portions of the key levers and for connecting linkage between the key levers and type bars. The key levers have downwardly and rearwardly inclined portions substantially parallel with the bars, said portions of the central levers lying closely below the central bars and extending close to the base of the main frame at the rear ends of the levers.

On the upper rear portion of the main frame is mounted a work carriage indicated

generally at 18 supporting the usual platen roller 19 on which the work is carried. At 20 is indicated a ribbon supporting and feeding means and at 21 is a guide for the ribbon adjacent the printing point. It will be observed that the work or platen carriage and the platen thereon are supported above and to the rear of the inclined type bar supporting means and at a much lower level than is usual in visible writing machines of the swinging bar type, the main frame 10 being quite low or flat with its highest point approximately level with the rear or highest bank of keys carried at the forward ends of the system of fore-and-aft extending key levers 12. It will also be observed that the ribbon supporting and feeding means is located forward of the segment plate, in the rear of the free ends of the type bars, and between the horizontal levels of the uppermost point of the platen and the lowermost point of the frame so as not to increase the height of the machine and so as to occupy the free space afforded within these bounds by the general arrangement of the adjacent parts and devices.

The carriage is supported on the main frame for longitudinal word-spacing, feeding movement by means of the usual or any suitable construction comprising, for example, the usual guide rails 21^a movable over a bed plate 31 carried by the usual shift frame (not shown) movable on the main frame to each printing case, which construction, therefore, requires no detailed description herein. The carriage is moved or fed by suitable motive means such as a spring drum indicated generally at 22, Figure 1, and including a pulley 23 on which is wound a flexible element (not shown) connected with the carriage as well understood in the art. The feeding movement of the carriage produced by the spring motor is controlled by an escapement or rack and pawl means comprising a rack bar 25 on the carriage with which cooperate a pair of pawls 26 and 27. It will be noted that the pulley and spring drum, and also the escapement mechanism comprising the rack and the pair of pawls or dogs cooperating therewith, are all arranged in the space afforded within the rear part of the main frame between the segment member or plate and the rear wall of the frame and between the lower part of the platen carriage and the base of the main frame, and that the lower part of the carriage and the bed plate 31 upon which it is guided are relatively close to the level of the upper edge of the plate 15 and the rear bank of keys and support the platen at a low point in position to be struck by the type bars after said bars have been turned on their pivots from upwardly and forwardly inclined normal positions substantially at right angles to the plate to upwardly and rearwardly in-

clined printing positions substantially parallel with the plate. Pawl 26 is pivotally supported at its lower end on a spindle or screw 28 carried between spaced ears 29 on a bracket 30 depending from the carriage bed 70 plate 31. Pawl 27 is pivoted on pawl 26 as at 32 and pawl 26 has a laterally projecting arm 33 to which is fixed one end of a tension spring 34 the other end of which is fixed to a bracket 35 extending rearwardly from 75 bracket 30. This spring serves to maintain the pawls in the position shown in Figure 2 with pawl 27 in engagement with the carriage rack. These pawls are connected by 80 spring and stop means or otherwise to provide the form of escapement well known in the art, being moved forwardly and backwardly to bring them alternately into engagement with the rack and to permit the latter and the carriage to move tooth by tooth under the actuation of its spring motor. The means for so moving the pawls comprises in the present instance a bell crank lever 36 pivoted at 37 on a bracket 38 extending rearwardly from the transverse wall 15. 85 One arm of this lever is positioned for engagement with the lateral arm 33 of pawl 26 and the other arm of the lever carries an adjustable contact screw 38^a for engagement with an arm 39 fixed on a rod 40 pivotally supported at its ends in downwardly and rearwardly extending brackets 41 on wall 15. The pawl engaging arm of lever 36 extends upwardly behind the escapement mechanism to a point close to the carriage bed 100 while the screw-carrying arm of said lever and bracket arm 38 extend under a part of the escapement mechanism. Rod 40 has fixed thereon also a pair of upwardly and rearwardly extending and transversely spaced 105 arms 42 having at their upper ends a loose connection with the rear ends of downwardly and rearwardly extending side arms 44 sliding in openings in wall 15 and carrying in front of the latter a sector 45 so positioned as to be struck by the type bars in the movement of the latter to printing position. The sector 45 and side arms 44 constitute a universal means or bar guided and supported entirely on plate 15 for oblique movement substantially at right angles to the plane of said plate and the type bar pivots, the arcuate member 45 of the universal bar lying close to the plate and being located closely above and curved about the pivoted ends of the system of type bars supported on the plate for actuation by the heels of the type bars. Arms 44 move downwardly and rearwardly in paths at opposite sides of the pawls when member 45 is struck by a type bar. The arrangement of escapement and universal bar mechanism shown and described is very compact but permits the use of substantial and sturdy parts without interference. It also provides a rapid and ac- 110 115 120 125 130

curate letter feed mechanism as the escapement is controlled by the heels of the type bars and the universal bar is accurately guided and held against cocking so as to act on the escapement uniformly irrespective of the position of the type bar in the segmental series of bars. It is evident that as one of the type bars is so moved it operates sector 45 and, through the train of mechanism described, oscillates rod 40 and bell crank 36 to move the pawls 26 and 27 back and forth across rack 25 to effect a step by step movement of the latter and of the carriage, as well understood in the art. It will be noted that the lever or interponent 36 engages dog 26, which is the rigid dog of the escapement, between the pivot of the dog and its nose or free rack-engaging end. This arrangement contributes to compactness.

The work carriage is shown as having the usual marginal stop means comprising a portion or bar 46, Figure 1, provided with notches 47 and with clips or stops 48 of the usual or any suitable construction adapted to be slidably positioned on the carriage for cooperation with suitable stops on the frame to limit the movement of the carriage.

The carriage locking and escapement disconnecting improvements, generally speaking, comprise means for locking the carriage in position on the frame and for disconnecting the escapement mechanism controlling the movement of the carriage, so that the force of the spring tending to move the latter is borne by the carriage locking device. Such means serve to maintain the carriage securely in position so that it cannot be shifted by jarring or bodily movement of the machine and at the same time, by disconnecting the escapement mechanism, protect the latter against undue strain and injury. These features are particularly advantageous in conjunction with machines of a portable type for safeguarding them during transportation. Such machines are commonly provided with casings for enclosing them during transportation and the present invention comprises, furthermore, a construction and arrangement of parts providing for automatic operation of the carriage locking and mechanism disconnecting devices when the casing is moved to position to enclose the machine.

Referring to the drawings for a more detailed description of these protective features, the lower end of bracket 30 is shown as provided with a rearwardly turned ear 49 on which is movably or pivotally supported, as at 50, a member or lever 51. The latter carries a part or dog 52 having a bevelled upper edge for engagement with any of the notches 47 of the marginal stop bar, when the lever is moved forwardly of the machine, as shown in Figure 3, thus securely locking the carriage in position.

Lever 51 is also provided with a finger 53 extending through an opening in bracket 30 into position for engagement with escapement pawl 26, for throwing both pawls forwardly out of engagement with the carriage rack when the lever is moved forwardly as described, thus completely disconnecting the carriage and the mechanism controlling its movement. A spring 54 coiled about finger 53 between the lever and bracket 30 serves to normally urge the lever rearwardly to inactive position, in which direction its movement is restrained by the hooked forward end of dog 52 which engages with a fixed stop 55 on the frame, as shown in Figure 2.

The machine is shown in combination with a casing comprising a base portion 56 on which the machine rests and a cover portion 57 hinged to the base portion at 58. When the cover portion is thrown rearwardly the machine is ready for operation, but when the cover portion of the casing is moved to position for enclosing the machine the rear wall of the cover, which is preferably provided with an abutment 59 for the purpose, engages lever 51, moving the same forwardly and automatically locking the carriage and disconnecting its controlling mechanism, so that the machine is placed in condition for transportation without danger of injury to its parts. Various modifications of the casing may obviously be employed and adapted in conjunction with lever 51 for actuating the latter as described.

The operation of the present improvements has been explained in connection with the description of the construction of the same. Lever 51 may, of course, be operated by hand and provided with any suitable detent means for retaining it in operating position, but it is preferred to arrange the lever as described for operation by the casing so that whenever the machine is closed for transportation the carriage is automatically locked and its controlling mechanism disconnected without requiring attention. Lever 51 is of course shiftable with the escapement frame or bed plate to each printing case and operates in any shifted position of the carriage. The carriage is locked in such a way as to effectively prevent any movement thereof in any position in which the machine may be placed and the disconnection of the carriage controlling mechanism relieves the latter of all strain, which is thrown upon the carriage locking device. The construction is exceedingly simple in form, comprising but few parts, a result attained in part by reason of the advantageous combination of the same with the usual parts of the typewriter. That is to say, in locking the carriage, use is made of the usual notched bar or rack commonly provided as a part of the marginal stop means.

120
125
130

Similarly, advantage is taken of the usual pivotal mounting of the pawl means controlling the feeding movement of the carriage, for moving the pawls to disconnect them, so that special construction of the parts of the typewriter proper is not required. The provision of the typewriter with the features of the present invention renders the machine safe for transportation without danger of injury to its parts, or any attention on the part of the operator.

I claim as my invention:

1. A typewriting machine comprising a frame, a work carriage, mechanism for moving said carriage on the frame to feed the work, a cover for the machine, and a locking device on said frame actuated automatically by the application of said cover for locking said carriage in any of its substantially central positions to protect the same and said mechanism during movement of the machine.

2. A typewriting machine comprising a frame, a work carriage, mechanism for moving said carriage on the frame to feed the work, a cover for the machine, and a device on said frame actuated automatically by the application of said cover for locking said carriage against inadvertent movement and provided with means for disconnecting said mechanism to protect the latter and said carriage against injury during movement of the machine.

3. A typewriting machine comprising a frame, a work carriage movable on the frame and having a portion provided with a plurality of notches spaced from one another in the direction of movement of the carriage, a cover for the machine, and a locking device on the frame actuated automatically by the adjustment of said cover into engagement with the notches of said portion for locking the carriage against inadvertent movement.

4. In a typewriting machine, the combination with a frame and a traveling work carriage thereon provided with marginal stop means including a notched portion extending in the direction of travel of the carriage, of a lever movably supported on the escapement frame and having a part for engagement with the notches of said stop means for locking the carriage against inadvertent movement.

5. In a typewriting machine, the combination with a frame, a work carriage having a feeding movement thereon provided with marginal stop means including a notched portion extending in the direction of movement of the carriage, and mechanism for spacing the latter arranged for disengage-

ment therefrom, of a protective device movable on the escapement frame for disengaging said mechanism and carriage and for engaging the notches of said stop means to lock the carriage against inadvertent movement.

6. In a typewriting machine, the combination with a frame, a work carriage having a feeding movement thereon provided with marginal stop means including a notched portion extending in the direction of movement of the carriage, and mechanism for spacing the latter including a rack and pawl means arranged for disconnection from each other, of a lever movably supported on the escapement frame having means for engagement with the notches of said stop means and with said mechanism for locking the carriage in position and disconnecting said rack and pawl means to protect said parts from injury by inadvertent movement.

7. A typewriting machine comprising in combination a work carriage, mechanism for spacing said carriage to feed the work, a locking device for locking said carriage in position, a device for disconnecting said mechanism, and a casing for the machine operating automatically upon movement to position to enclose the latter, to actuate said devices for protecting the parts against injury during movement of the machine.

8. A typewriting machine comprising in combination a work carriage, mechanism for spacing said carriage to feed the work, a movable member provided with means for locking the carriage in position and with means for disconnecting said mechanism and a casing for the machine operating automatically, upon movement to position to enclose the latter, to move said member to lock the carriage and disconnect said mechanism.

9. In a typewriting machine, the combination with a frame, a work carriage having a feeding movement thereon provided with marginal stop means including a notched portion extending in the direction of movement of the carriage, and mechanism for spacing the latter including a rack and pawl means arranged for disconnection from each other, of a lever movably supported on the escapement frame having means for engagement with the notches of said stop means and with said mechanism for locking the carriage in position and disconnecting said rack and pawl means, and a casing for the machine operating automatically, upon movement to position to enclose the latter, to move said lever to lock the carriage and disconnect said mechanism.

GEORGE F. ROSE.
